UNITED STATES PATENT OFFICE.

ADAM WILLIAM FELTMANN, OF CHICAGO, ILLINOIS.

DENTAL TOOL.

No. 799,724.

Specification of Letters Patent.

Patented Sept. 19, 1905.

Application filed December 27, 1904. Serial No. 238,313.

To all whom it may concern:

Be it known that I, ADAM WILLIAM FELTMANN, a citizen of the United States, residing at Chicago, in the county of Cook and State 5 of Illinois, have invented new and useful Improvements in Dental Tools, of which the following is a specification, reference being had to the accompanying drawings, forming a part thereof.

10 This invention relates to devices particularly adapted for dentists' use, but not limited to such use, for releasably holding small articles which are to be ground, dressed, or polished, its specific features being contrived 15 with reference to the function of holding artificial porcelain teeth in the process of dressing the same.

It consists of the features of construction set out in the claims.

20 In the drawings, Figure 1 is a side elevation of such hand-vise. Fig. 2 is an axial section on a larger scale than Fig. 1. Fig. 3 is a transverse section at the line 3 3 on Fig. 1 on a magnified scale.

25 This tool comprises an outer barrel or sleeve 1, within which is the longitudinally-reciprocating plunger 2, which protrudes at the upper or rear end from the barrel or sleeve and at the opposite end has made fast to it the spring-gripper 3, comprising upper and lower jaws 3^a and 3^b, respectively, constructed so that normally they stand spread to a distance greater than the diameter of the barrel 1, as seen in Fig. 2, but having sufficient elasticity to be closed together for gripping as they are drawn into the barrel. The plunger 2 is reduced in diameter to accommodate a spring 4, which is coiled about the plunger within the barrel or sleeve, being 35 stopped at the forward or lower portion extending to the end having the gripping-jaws, such reduction forming a forwardly or downwardly facing shoulder 2^a at one end against said shoulder 2^a and at the other end against

40 stop screws or studs 5, which are inserted through the sleeve from the outside for that purpose, as seen in Fig. 2. This spring thus reacts between the fixed stops 5 of the sleeve and the shoulder 2^a on the plunger for yieldingly resisting the protrusion of the spring-gripper 3 and elastically reacting to withdraw said gripper into the sleeve with a tendency to close up the jaws upon whatever article may be lodged between them for the purpose 45 of being gripped by them. The plunger 2 is axially bored and is also counterbored through-

out the greater portion of its length, the portion not counterbored being threaded internally, whereby the plunger is adapted to admit through it the threaded shaft 6, which is 60 screwed through the threaded portion of the plunger and carries on the end which protrudes within the spring-gripper 3 a head-block 7, preferably swiveled on the end of said shaft 6, and adapted for backing up or 65 stopping at the back or inner end the tooth-blank or other piece of work which may be grasped between the spring-jaws. For the further specific purpose of steadyng or rendering fixed in position the inner end of 70 such piece of work when this is desirable by reason of the shape of the work and the position of the face which is to be dressed the head-block 7 has a conical recess 7^a, which is adapted to receive and to center in a conically- 75 tapering piece of work, and for the purpose of similarly engaging and thereby steadyng a piece which may have a wedge taper, but not a conical taper, which would permit it to enter the conical socket 7^a, the head-block 80 has a V-shaped notch 7^b cut diametrically across its forward face or end to less depth, preferably, than the conical socket, but sufficient to afford lodgment for a wedge-shaped edge of a tooth-blank, as seen in Fig. 1. 85

It will be seen that the operator holding this tool between two fingers of the hand can operate the plunger by means of the thumb pressed against the upper or rear end or against the corresponding end of the stem 6, 90 which being screwed through the plunger is positively engaged with it for endwise movement, and that such pressure of the thumb upon the upper or rear end of the plunger advancing the spring-jaws permits them to 95 spread to release any piece of work which may be held in them, and that when thus held the operator may adjust to the jaws and the head-block any piece of work which is to be held in the device, and upon releasing the 100 pressure upon the plunger the spring 4, operating to retract the plunger into the sleeve or barrel 1, causes the barrels to be closed together for gripping the work more or less firmly, according to the tension of the spring. 105

For holding the work with sufficient firmness to permit it to be dressed or ground it is necessary to provide some more positive means than the spring 4, and for this purpose the plunger is reduced in diameter at its rear upper portion from the upwardly or rearwardly facing shoulder 2^b and has on this re-

duced portion an exteriorly-threaded sleeve 8, which is stopped longitudinally between the shoulder 2^b and the retaining-collar 9, secured to the upper or rear end of the plunger, 5 the sleeve being free to rotate easily on the plunger between the stops which retain it. For engaging the exterior thread of this sleeve 8 a segmental nut or piece of a nut 10 is provided, the same being set through the outer 10 sleeve or barrel 1, which is apertured to accommodate it or seat it. This segmental or fractional nut 10 may be retained in its seat or aperture in the barrel 1 by means of spring-fingers 11, which clasp the barrel lightly, so 15 that while holding the nut normally engaged with the thread of the sleeve they permit disengagement in the manner contemplated by the ratchet formation of the thread. This fractional nut, however, is more forcibly held 20 in engagement at its threaded interior side and with the exterior thread of the sleeve 8 by means of a spring 12, which is made fast in any convenient manner, as by soldering, to the outer surface of the barrel 1, and which 25 has a free end 12^a engaged with the boss 10^a of the nut. The thread of the sleeve 8 and nut 10 is ratchet-formed, having an abrupt face to the rear or upper end and a long slope to the lower or downward end of the implement, and the spring 12 normally bears upon 30 the nut with moderate force only, not sufficient to prevent the sleeve being pushed longitudinally downward or forward for protruding the spring-jaws to release the article 35 held therein or to spread them for receiving a piece of work, the ratchet-thread of the sleeve in such action slipping by the ratchet-thread of the nut in a manner which will be obvious. It will be observed also that when 40 the plunger is thus thrust down or forward to protrude the jaws and permit them to spread the fractional nut operates as a detaining-dog engaging the ratchet-thread and prevents the spring 4 from retracting the 45 plunger to close the jaws, so that the operator may readily adjust any piece of work in the jaws, which may then be retracted by rotating the threaded sleeve 8 until the work is properly gripped; but it will be seen that the 50 grasp which can be thus obtained upon the work in the jaws will be limited by the pressure which the spring 12 exerts upon the fractional nut 10, and in order that this pressure may be made adequate to hold the 55 work firmly the spring is constructed, as shown clearly in Figs. 1 and 2, with a refolded portion 12^b, which extends under or within the outer terminal portion 12^a, and where the two portions 12^b and 12^a lap one within the other 60 a slide block or clamp 13 encompasses both of them, and by sliding this clamp one way or the other along the lapped portions the length of the free end of the spring which is unrestrained in its elastic reaction upon the nut 65 may be varied, and the pressure which will

thus be exerted to hold the nut in engagement with the sleeve may be increased by moving the slide 13 toward the rear or upper end for shortening such free portion of the spring or in the opposite direction for lengthening it. 70

In order that the slide may be retained without danger of slipping away from the position at which the free portion of the spring is shorter, one of the lapped portions of the spring is at that point curved away from the other, so that the slide compresses them together in order to encompass them at this point, as seen at Fig. 2, and is thereby frictionally held at that position, or if moved a little beyond it is more certainly prevented 80 from slipping back. In order that the rotation of the threaded sleeve 8 shall effectually operate to retract or protrude the plunger, the latter is prevented from rotating in the barrel 1 by means of gudgeon-screws 14, 85 which are set into the plunger through the barrel from opposite sides where the barrel has slots 15, 15 provided for that purpose long enough to accommodate the entire longitudinal movement which it is at any time 90 necessary to give the plunger.

For the specific purpose of holding the artificial-teeth blanks for dressing them the particular form of jaws shown in the drawings is desirable, the lower jaw being protruded 95 beyond the upper and the upper being recurred inward toward the lower, so that while the lower jaw forms a seat or rest for the blank 16 the upper jaw may engage it at either side of the rivets 16^a. 100

I claim—

1. In a tool for the purpose indicated, in combination with the exterior element or barrel, a plunger reciprocating in the barrel and having gripping-jaws which are operated by such reciprocation, and a ratchet-threaded connection between the plunger and the barrel, one of whose elements is elastically yielding with respect to the other for disengagement of the threaded connection. 105 110

2. In a tool for the purpose indicated, in combination with the exterior element or barrel, a plunger reciprocating in the barrel and having gripping-jaws protruding therefrom which are operated by such reciprocation; a spring reacting between the plunger and the barrel for yieldingly resisting the longitudinal movement of the plunger in one direction, and two elements constituting a threaded connection between the plunger and the barrel, one of said elements being rotatable for longitudinally moving the plunger, and one of them also being movable for disengagement of the threaded connection to permit such longitudinal movement independently of the 120 threaded connection. 125

3. In a tool for the purpose indicated, in combination with the exterior element or barrel, a plunger reciprocating in the barrel having gripping-jaws protruding therefrom which 130

are operated by such reciprocation; a spring reacting between the plunger and the barrel for yieldingly resisting the longitudinal movement of the plunger in one direction and reciprocating it in the opposite direction, and a ratchet-threaded connection between the plunger and the barrel, one of whose elements is elastically yielding with respect to the other for disengagement of the coöperating parts at such threaded connection.

4. In a tool for the purpose indicated, in combination with an exterior element or barrel, a plunger extending longitudinally within the barrel having at one end gripping-jaws which protrude from the barrel which are operated by the reciprocation of the plunger, and a shaft which extends axially through the plunger having threaded engagement therewith, such shaft terminating between the jaws back of their gripping-terminals.

5. In a tool for the purpose indicated, in combination with the exterior element or barrel, a plunger extending longitudinally within the barrel having at one end gripping-jaws protruding from the barrel and operated by the reciprocation of the plunger; a spring reacting between the barrel and the plunger for giving the latter longitudinal movement in the direction for closing the jaws, and a shaft screwed through the plunger having a head which protrudes between the jaws back of their gripping-terminals, such head having a conical socket for seating the work which may be gripped by the jaws.

35 6. In a tool for the purpose indicated, in combination with the exterior element or barrel, a plunger extending longitudinally within the barrel having at one end gripping-jaws which protrude from the barrel and are operated by the reciprocation of the plunger; a shaft screwed through the plunger and protruding between the jaws, and a head swiveled on such protruding end of the shaft having a transverse V-shaped notch in its forward end or face.

7. In a tool for the purpose indicated, in combination with the exterior element or barrel, a plunger reciprocating in the barrel and having gripping-jaws protruding from the latter adapted to be closed by retraction into the barrel and spread by protrusion therefrom; a spring reacting between the barrel and the plunger to retract the jaws into the barrel; an element on the plunger having an exterior ratchet-thread; a coöperating element mounted on the barrel for engaging the ratchet-thread, and a spring tending to hold the same into engagement with the thread, said thread having its abrupt shoulder facing rearward or upward, whereby the thread element is adapted to be forced forward or downward.

8. In a tool for the purpose indicated, in combination with an exterior element or barrel, a plunger extending longitudinally within the barrel and having at one end gripping-jaws

which protrude from the latter; a spring reacting between the plunger and the barrel to retract the jaws; a sleeve longitudinally stopped on the plunger and rotatable thereabout, exteriorly threaded, the plunger being engaged with the barrel for preventing rotation relatively thereto, and a nut device engaged with the barrel against longitudinal displacement, but movable for engagement with and disengagement from the thread of the sleeve, and means for releasably holding it engaged therewith.

9. In a tool for the purpose indicated, in combination with the exterior element or barrel, a plunger extending longitudinally within the barrel and having at one end gripping-jaws protruding from the barrel; a sleeve longitudinally stopped on the plunger and rotatable thereabout, exteriorly threaded; a nut device longitudinally stopped on the barrel for engaging the sleeve; a stem or shaft extending axially through the plunger and having threaded engagement therewith, such stem protruding between the jaws, and a head carried by the stem between the jaws back of their gripping-terminals.

10. In a tool for the purpose indicated, in combination with the exterior element or barrel, a plunger extending longitudinally within the barrel and having at one end gripping-jaws protruding from the barrel; a sleeve longitudinally stopped on the plunger and rotatable thereabout, exteriorly threaded; a nut device longitudinally stopped on the barrel for engaging the sleeve; a stem or shaft extending axially through the plunger and having threaded engagement therewith, such stem protruding between the jaws, and a head carried by the stem between the jaws back of their gripping-terminals, said head being swiveled on the stem and provided with a transverse notch for engaging the work.

11. In a tool for the purpose indicated, in combination with the exterior element or barrel, a plunger extending longitudinally therein, having at one end gripping-jaws protruding from the barrel; a spring reacting between the plunger and the barrel to retract the jaws; a sleeve longitudinally stopped on the barrel and rotatable thereabout, exteriorly threaded; a nut device longitudinally stopped on the barrel engaging said threaded sleeve, and movable for disengagement therefrom; a spring mounted on the barrel for holding it in engagement, and means for tensioning the spring.

12. In a tool for the purpose indicated, in combination with an exterior element or barrel, a plunger extending longitudinally therein having at one end gripping-jaws protruding from the barrel adapted to be closed together by being retracted into the barrel; a spring reacting between the plunger and the barrel for so retracting the jaws; a ratchet-threaded sleeve rotatably mounted and longi-

tudinally stopped on the barrel; a corresponding ratchet-formed nut element for engaging the ratchet-thread of the sleeve, said ratchet-thread having its abrupt shoulder facing rearward for positive engagement with the nut against retraction rearward; a spring mounted on the barrel having a free end pressing on the nut for holding it in engagement with the ratchet-threaded sleeve, and a slide movable longitudinally along the spring to vary

the length of its free portion for tensioning the same.

In testimony whereof I have hereunto set my hand, in the presence of two witnesses, at Chicago, Illinois, this 28th day of November, 1904.

ADAM WILLIAM FELTMANN.
